UNITED STATES PATENT OFFICE

ALFRED T. BROWN, OF CINCINNATI, OHIO, ASSIGNOR TO THE WARNER ELEVATOR MANUFACTURING COMPANY, OF CINCINNATI, OHIO, A CORPORATION OF OHIO

SAFETY DEVICE FOR ELEVATORS

Application filed September 26, 1930. Serial No. 484,515.

My invention relates to a safety device for an elevator system having for its object the provision of means controlled by the car travel for automatically rendering the car door inoperative intermediate floors and automatically rendering it manually and unitarily operative with the hatchway floor door when the car and building floors are in alignment.

Whilst the invention has safety utility in any elevator system employing horizontally sliding car doors which may or may not be used with sliding doors, its field of particular utility as regards modern elevator practice, comprises the application of the concept herein disclosed to an elevator system which employs the unit motor mechanism door control in the car, or shaftway, wherein the safety devices are in the nature of automatisms not within the control of the operator, that is to say, no malfunction is possible.

The features of my invention are more fully set forth in a description of the accompanying drawings forming a part of this specification, in which :

Figure 1 is a central vertical section of an elevator shaft and hatchway.

Figure 2 is an enlarged view taken at one of the lower sections.

Figure 3 is a section on line 3—3 of Fig. 2.

Figure 4 is a view taken the same as Fig. 1, but showing modifications.

Figure 5 is a view taken the same as Fig. 2, but showing modifications.

Figure 6 is a section on line 6—6, of Fig. 5.

A section of the elevator shaft showing the floors and hatchway is illustrated, wherein 1 indicates the wall of the elevator shaft, 2 the building floor, 3 the elevator car floor, 4 the hatchway floor door, 5 the car, and 6 the car door.

The safety mechanisms comprise interlock instrumentalities in the nature of mating male and female members, one set of said members, say the male components, being serially disposed in precise vertical alignment with one another, attached on the one wall of the shaft, one between each floor, and on the shaft face of the hatchway floor door.

50 The coacting member, say the female com-

ponent, is secured to the outer face of the car door for telescopic engagement with the male members during the elevator travel and when the car door is closed.

Whilst I have shown for simplicity, interlocking members of the species comprising a channel member and series of channel riding members, rails or rollers, forming an accurate guide for the moving and stationary interlocking devices, it is observable that the relative position of the male and female members can be transposed, and also, that the exact structure of the interlocking devices is not necessarily of limiting import.

In the form shown by way of example, the 65 female member comprises a channel iron 7 secured to the outer face of the car door. A series of male members shown as rail sections 8, Figure 2, or alternately as roller posts 9, Figure 4, are secured respectively to the inner 70 or shaft face of the hatchway floor doors and to the shaft walls intermediate the several floors. These stationary members of the safety interlock are in precise vertical alignment with one another and with the channel 75 strip 7 of the car door when closed, thus providing the telescopic action wherein the car member successively engages respectively the hatchway floor door and the shaft wall mating members in the interlock.

When the car floor and the building floor are in substantial alignment, the car and hatchway floor doors are operatively interlocked for unitary action under the control of the operator. When the members engage 85 interlocked the floors, the car door is interlocked in relation to the wall of the elevator shaft, i. e. it is rendered inoperative.

Inasmuch as the car door cannot be horizontally shifted between floors, the car door 90 mating member is accurately and rigidly held in correct position for invariable engagement and coaction with the mating members of each of the hatchway floor doors.

The fact that the car door in consequence 95 is always locked shut while the car is traversing between the floors, is not only a safety measure of great value but, as disclosed, the same instrumentality becomes a double door actuating device when, and only when the car 100

floor is in proper registry with the building floor. In addition to the safety feature, this invention provides a saving of time and effort and an invariability of result. From the structural viewpoint there is also the resulting economy in initial cost of equipment as well as in maintenance of the elevator service.

Having described my invention, I claim:

- 10 1. In combination with an elevator system employing horizontally sliding car and hatchway floor doors, a safety device comprising interlock instrumentalities on the opposing faces of the car and hatchway floor doors, and the shaft wall intermediate floors successively engaging during car travel, said instrumentalities functioning between floors to interlock the car door in relation to the shaft wall and to interlock the car and hatchway floor doors for unitary movement when the car and building floors are in alignment.
- 15 2. In combination with an elevator system employing horizontally sliding car and hatchway floor doors, a safety device comprising aligned interlock instrumentalities on the opposing faces of the car and hatchway floor doors, and shaft wall intermediate floors, successively engaging telescopically during car travel, said instrumentalities functioning between floors to interlock the car door in relation to the shaft wall and to interlock the car door and hatchway floor door for unitary movement when the car and building floors are in alignment.
- 20 3. In combination with an elevator system employing horizontally sliding car and hatchway floor doors, interlock instrumentalities constituting a safety device, said instrumentalities comprising aligned channel and channel riding members arranged for relative and successive telescopic engagement during car travel, the said members being respectively disposed on the opposing faces of the car and hatchway doors and of the shaft wall intermediate floors, enabling the hatchway floor door to be opened and closed by manipulation of the car door when the car and building floors are in alignment but rendering the car door inoperative intermediate floors.
- 25 4. In combination with an elevator system employing horizontally sliding car and hatchway floor doors, means controlled by the car travel, rendering the car door inoperative intermediate floors, and devices controlled by the car travel operatively connecting the car and hatchway floor doors when the car and building floors are respectively in alignment.
- 30 5. In combination with an elevator system employing horizontally sliding car and hatchway floor doors, a safety device comprising aligned interlock instrumentalities on the car door and shaft wall intermediate floors, rendering the car door inoperative intermediate floors, and means governed by the car travel operatively connecting the car and hatchway

doors when the car and building floors are in alignment.

6. In combination with an elevator system employing horizontally sliding car and hatchway floor doors, coincidentally aligned interlock members on the inner faces of the hatchway doors and the shaft wall intermediate floors, and a mating interlock member on the car door arranged for successive telescopic engagement with said first named members, holding the car door inoperative intermediate floors and rendering the hatchway floor door unitarily operative with the car door when the car and building floors are aligned.

7. In combination with an elevator system employing a horizontally sliding car door, devices disposed in the hatchway and on the door of the car, said devices interlocking intermediate the floors for preventing opening of the car door when the car is not in substantial registry with the floors.

In witness whereof, I hereunto subscribe my name.

ALFRED T. BROWN.
